Application November 18, 1938, Serial No. 241,177

10 Claims.

(Cl. 41—21)

The invention relates to improvements in dye printing photographic processes in which matrix films representing text, tone or color part values are first provided with transferable coloring substances and then printed in register or special alignment on a blank. The invention concerns the registration step in regard to when and how such step can be performed with advantage in the course of the reproduction process. In combination with old steps the invention greatly simplifies the mechanical reproduction and is particularly suitable for color photography. By permanently combining in a unit tangible elements at a certain stage of the process the new step is materialized in a product.

One of the purposes of the invention is to eliminate the use of auxiliary devices for registering matrix films or part images printed in different blanks. This purpose is attained by producing the printing matrices on a material having an elastic support, providing a sufficient margin at one end of the matrices, bringing the matrices into register, and then permanently attaching said matrices at said margin in book-like form, as for instance by soldering or riveting once and for all the printing matrices to each other. Due to the elasticity of their support and the margin left the film matrices though attached in register permit enough separation for their inking and for inserting the printing blank and produce the picture in known manner. This new permanent registration cannot be practiced when the matrices are all produced in material of rigid support, as ordinary plates, and is also unapplicable to the production of cinematographic length of film for in this case matrices and blank have the same width and no margin can be provided. But such limitations are unimportant because Celluloid supported films have practically ousted today photographic plates and because the moving picture production rather requires auxiliary devices for a great output in a sort of mass production of pictures. The advantages of the new step are however, priceless for the ordinary photographer or amateur who cannot afford an installation including registering devices of great precision to produce a small number of pictures.

Another purpose of the invention is the saving of time. In two color work, for instance, whether two matrices or two blanks bearing different part images, have to be registered, that operation, either by machine or hand, must be repeated for every picture and in the last case the blank must also be glued. While according to the invention two matrices permanently bound face to face, and registered once, will print part records in register on opposite sides of a transparent double coated support as many times as desired in a single and final operation. The regis- 60

tion made once will serve not only for the first picture but for all the pictures produced from said matrices which are printed, washed, dried and filed for future use in such bound condition, so that not only a registering device but the registration itself is further unnecessary.

Another purpose of the invention is the protection of the delicate matrix films during their handling for it saves them from scratches and other common accidents. When the matrices are two, assembled face to face, the images are inside and the bare Celluloid out, while the permanently attached margins do not permit any sliding which could result in harmful friction. 15 This is particularly important when the matrices after printed are filed for future use, as it is well known that old loose matrices are usually worthless and ruined. When the matrices are three, I assemble one pair face to face and the other face out but facing an auxiliary element or extra piece of plain Celluloid for protection. If only transparencies were to be printed the odd matrix could be protected by the back of one of the pair, but for all purposes I prefer to add the extra protecting cover.

Another purpose of the invention is to provide a system of registration suitable not only for two but for three or four color work. I may use a blank formed by two separate elastic elements 30 which I attach or solder exactly as I do with the matrices at one margin. It must be observed that I do not use a marginally soldered pair of blanks for two color work where a double coated single blank is sufficient but for producing three or four color pictures. It must also be noticed that the two element blank which I use for three or four color work is formed as explained by two separate parts and that these parts are bound as the matrices. Only in that condition the registration is dependable for as it is well known the position of a plane is determined by three points and, when two elements are soldered or riveted, the attached sections occupy enough surface to secure the position of the printing planes. In other words, the matrices or the two bound blanks can be partially separated because the material is elastic and not because the planes have any play upon a doubtful axis as the folding line of a double blank made from a single piece of material and which would require additional precautions to secure registration almost equivalent to those required for the registration of two loose blanks.

In the drawings:

Fig. 1 represents as example one pair of positive matrices.

Fig. 2 shows the same matrices permanently soldered and fastened to each other.

Fig. 3 illustrates a set of three permanently at-

tached matrices with a protecting fourth element.

Fig. 4 is a set of four marginally and permanently bound matrix films.

Fig. 5 is a combination of pictorial and text matter in two attached matrices.

Fig. 6 shows two attached pigmented matrices.

Fig. 7 illustrates a separating marginal strip between attached matrices.

Although the invention is suitable for different methods of dye transferring and capable of serving different purposes in mechanical printing, we shall present as example of its reduction to practice a color photographic reproduction made by the well known wash-off process.

In Figure 1, a pair of two color separation matrix films 1, 2, are represented. I may produce these matrices by the known wash-off process and in the known material having an elastic support of Celluloid. As shown in the figure the complementary part images are printed so that they may be brought in register when the gelatine sides of both matrices are facing each other. Those reliefs are produced with a sufficient margin for the soldering shown in Fig. 2. I practice this by wetting and brushing away part of the gelatine in contacting sections at one end of both reliefs, and after bringing the images in register I carefully apply to the bare Celluloid of both elements the well known film cement, 5, or an equivalent. I may also place between the soldered margins an auxiliary element consisting of an intermediate strip of Celluloid 6, Fig. 7, to which both matrices are soldered in order to separate the printing planes in the thickness of the blank. This soldering of course can be performed by other means as rivets (5b), eyelets (5a) or any suitable means that would firmly and permanently bind the matrices at the margin and preserve the registration without interfering with a partial separation of the matrix films as the leaves of a book.

For the coloring of the bound matrix films any known means with some suitable modifications may be used, as a two cell tank having the complementary coloring solutions separated by a partition, the margin allowed in the matrix films permitting to interlock said partition between the bound matrices and thus selectively dye each one with a different color.

I prefer however, to apply the dyes in another form and by either one or two new methods of my invention which I have successfully practiced. Besides being equally efficient and far superior from several points of view to the old dyeing bath system, those methods present a particular advantage for the coloring of bound matrices in color photographic reproduction, and that is that the colors are carried to the surface of the matrix films by sheet-like thin elements. This permits to reduce to a minimum the margin on each matrix because the necessary separation to insert said dyeing elements is very small and so the soldered matrices having less play are still more accurately registered.

One of the dyeing methods of my invention that I use consists in separately applying in succession to the matrix films the dry and the liquid components of a dyeing liquor. I first take two cut pieces of a sheet like medium, tissue, porous paper or equivalents which have been impregnated with complementary dyeing solutions in concentrated form and which contain in dry state the corresponding dyestuffs and dyeing assist-

ants, and I place in contact with each matrix film respectively the dry colored sheets. Then I take a lintless blotter, or better a waterproof support double coated with thin, lintless blotter or equivalents, and imbibe this element in the liquid component of the dyeing liquor which is a weak solution of glacial acetic acid or equivalent and I insert the liquid holding element between the sheets already in contact with the matrix films. In that manner, and by gently squeegeeing I produce in a simple way the dyeing liquor at the very surface of the matrix films and then allow the necessary time for their selective inking.

Another means that I may use for inking the bound matrix films and which is particularly suitable for wash-off reliefs is the polychromatic pad of my invention. Such pad consists of a thin waterproof support carrying on each side gelatine or equivalent medium in which a different coloring substance in dry state is respectively incorporated. Although this pad is of different types and may supply more than two colors, the one described serves the purpose for the present disclosure. For wash-off matrix films the dyeing pad may be made by double coating the support with hard gelatine amounting to 0.25 grammes per 100 cm.² and 0.03 to 0.05 grammes of selected acid dyes for the same surface. The pad, being in dry condition, needs to be soaked for about 5 minutes in water to produce the dyeing liquor in the gelatine. For that purpose a weak solution of glacial acetic acid is satisfactory, where the selected colors do not bleed. For the inking the soldered matrices are wetted in a weak solution of ammonia to produce an alkalinity which increases the affinity for acid dyes as it is well known in the tintorial industry. The sandwich is then made, squeegeed and kept for a few

40 Besides those described other means may be used for selectively dyeing the soldered matrices, although the last two are most suitable for several advantages among which their simplicity and cleanliness.

45 After the matrices are inked, Fig. 6, the coloring element is extracted and the known mor-
danted double coated blank Fig. 7, previously
soaked in water is introduced between the mat-
rices, squeegeed to contact and left for a few
50 minutes. Then the finished picture is extracted
and dried.

Outfit

Two wash-off soldered matrices
One coloring pad
One printing blank
Weak glacial acetic acid solution
Weak ammonia solution
A squeegee

Process

- 65 1. The pad is soaked for a few minutes in the acetic acid solution and the matrices wetted in the ammoniacal solution.
  - 1 2. The pad is interleaved between the matrices, squeegeed to contact and left for a few minutes.
  - 70 3. A blank is soaked in water, introduced in the place of the pad, squeegeed to contact, left for a few minutes and the finished picture is extracted.
  - 75 4. After the first printing the matrices may be

washed in ammoniacal water for a new pass. Before filing the bound matrices for future use it is advisable to leave them open for a few minutes until dry and so they will keep protected, in register and ready for printing at any time.

In the example presented a bicolor reproduction was considered. For three and four color work the book of matrices is permanently bound as shown in Figs. 3 and 4. It can be observed that the lower element in Fig. 3 has not an image but represents a plain piece of Celluloid to protect the odd matrix film. As to the coloring, two pads are necessary, each inking two matrices or the odd one; and in regard to the printing two blanks will be used, soldered as a book of matrices and then interleaved between the inked matrix films.

The use of bound matrix films is not only applicable to the wash-off process but to other methods involving the inking and printing of key images, with the obvious variation of dyeing liquors and coloring technique.

The book of matrices is not only useful for color photography, but also for combining photographic tone values for dichroic effects. It may also be used with advantage for simultaneous printing of records of different type on opposite sides of an opaque blank as an illustrated post card, Fig. 5, the registration amounting to the correct alignment of the text. These and many other possible applications show the useful character of the invention in connection with dye printing processes.

I wish to be understood that I do not pretend any invention in producing a picture by sandwiching a double coated blank between two colored matrix films in register for that is old. What I believe to be new is the step of putting the matrices face to face in register before they are inked; to provide in the same a margin which combined with the elasticity of the support permits to fix the position of the printing planes and still allows enough separation for the inking after the registration; to permanently bind said matrices face to face so as to protect them; to eliminate any auxiliary balky or unreliable device for registering; and to keep the matrices in book form and in register once and for all. As this last step materializes the invention in a set of matrices permanently bound and forming a unit which can be filed, sold or mailed in such condition, it seems that the scope of the invention is fully embodied in the book of matrices. The characteristics of the invention may thus be summarized in that the combination may include printing matrices and also auxiliary members, respectively arranged in cooperating printing position, attached at convenient sections of their margins and forming a unit.

It must also be understood that the present disclosure is for the purpose of illustration only and that my invention includes any equivalents or variations which fall within the scope of the appended claims.

I claim:

1. A plurality of printing matrix films suitable for pigment transferring, said printing matrix films having elastic supports and each one a margin, all of said matrix films attached together at said margin in book form, the margin and the elasticity of the support permitting sufficient sep-

aration between the attached matrix films for providing the same with transferable coloring substances and for interleaving between said matrix films a blank having a plurality of printing surfaces.

2. A plurality of printing matrices suitable for pigment transferring, said matrices respectively representing different tone values of the same subject, said printing matrices assembled in register and attached at one margin.

3. A plurality of printing matrices suitable for pigment transferring and representing, respectively, color part values of the same subject, said matrices in register and attached at one margin.

4. A plurality of printing matrices suitable for pigment transferring, and respectively representing different selected pictorial and text matter, said matrices arranged in register and alignment in regard to each other and attached at one margin.

5. An article including in a unit a plurality of marginally attached printing matrices in cooperating printing position and pigmented, the margins in said matrices sufficiently elastic to allow their partial separation, the unit in normal position presenting the appearance of several assembled films.

6. The combination of a printing matrix having an elastic support and another printing matrix also having a support, said printing matrices attached together at one margin, the printing side of one of the matrices facing the printing side of the other matrix, the supports protecting the inner printing sides of both matrices from harmful friction.

7. The combination of a sheet-like printing matrix and a similar sheet-like element, said matrix and said element attached to each other at one margin, said element facing and protecting the printing side of said matrix from harmful friction, and permitting sufficient separation to provide the matrix with transferable coloring substances and to interleave a printing blank between the matrix and the protecting element.

8. The combination of two sheet-like printing matrices and an interposed marginal strip attached together and maintaining the major portions of the matrices in separated relation for interleaving a blank therebetween, said strip and said blank substantially having the same thickness and the same contacting planes with said matrices.

9. An article comprising printing matrices and auxiliary elements attached at convenient sections of their margins in cooperating printing position and forming a unit, the margins in said matrices being elastic, the attachment of the matrices including sufficient area as to fix their respective printing planes, and the elasticity of their margins being enough to provide sufficient play for inking and printing purposes.

10. In a printing device formed by a plurality of attached elements forming a unit, a number of printing elements in cooperating printing position and having elastic margins attached to other elements, the elasticity of said margins and the attached sections providing hinges of great precision for successively printing in correct superposition the said printing elements.

F. G. YANES.
